(57) **CLAIM**

The ornamental design for a dental implant, as shown and described.

DESCRIPTION

FIG. 1 is a top-front-left perspective view of a dental implant showing my new design;

FIG. 2 is a bottom-rear-right perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a left-side perspective view of a second embodiment of a dental implant. The break lines indicate that any portion of the article beyond what is shown forms no part of the claimed design, that being the only difference from the embodiment shown in FIGS. 1 through 8.

The broken lines showing a hexagonal head screw are included for the purpose of illustrating environmental structure and forms no part of the claimed design.
